COMBINATION REFUSE AND ADVERTISING DISPLAY CONTAINER

William J. Lipscomb, Houston, Tex.

Application November 9, 1956, Serial No. 43,710

Term of patent 7 years

(Cl. D58—17)

The figure is a perspective view of a combination refuse and advertising display container showing my new design, the opposite sides being substantially the same as the sides shown.

I claim:

The ornamental design for a combination refuse and advertising display container, as shown and described.
